(57) **CLAIM**

The ornamental design of a insulated food container, as shown and described.

DESCRIPTION

FIG. 1 is a perspective view from above of our insulated food container design;

FIG. 2 is a perspective view from below of our insulated food container design and taken diametrically opposite from the view of FIG. 1;

FIG. 3 is a side elevation of our insulated food container design depicting it as it would appear at any angle about it; FIG. 4 is a plan view of our insulated food container design; and,

FIG. 5 is a bottom view of our insulated food container design.

The broken lines are for illustrative purposes only and form no part of the claimed design.
